Primary Examiner — Cynthia Ramirez

(57) **CLAIM**

We claim the ornamental design for a dish caddy adjusting lever, as shown and described.

DESCRIPTION

FIG. 1 shows a right side perspective view of the dish caddy adjusting lever.

FIG. 2 is a right side elevation view thereof.

FIG. 3 is a left side elevation view thereof.

FIG. 4 is a top plan view thereof.

FIG. 5 is a bottom plan view thereof.

FIG. 6 is a front elevation view thereof.

FIG. 7 is a rear elevation view thereof; and,

FIG. 8 is a left side perspective view of dish caddy adjusting lever.

1 Claim, 4 Drawing Sheets
